UNITED STATES PATENT OFFICE.

JOHN A. LE CAIN, OF MALDEN, MASSACHUSETTS, ASSIGNOR TO WORTHINGTON PUMP
AND MACHINERY CORPORATION, A CORPORATION OF VIRGINIA.

CHECK VALVE.

Application filed December 22, 1920. Serial No. 432,398.

To all whom it may concern:

Be it known that I, JOHN A. LE CAIN, a citizen of the United States, residing at Malden, county of Middlesex, and State of 5 Massachusetts, have invented certain new and useful Improvements in Check Valves, fully described and represented in the following specification and the accompanying drawings, forming a part of the same.

10 This invention relates to improvements in automatic check valves of that type cushioned on their opening movement to avoid pounding, the invention being especially applicable to exhaust check valves for use in 15 feed water heaters and the like, although applicable generally where such a cushioned check valve is of use.

One object of this invention is to provide a cheap, compact and efficient check valve 20 having means for regulating or adjusting the cushion.

25 A further object is to provide an improved and efficient device for cushioning the movement of such valves in both directions.

In the accompanying drawings forming a 30 part of this specification, the invention is shown as applied in preferred forms, and these constructions will now be described in 35 detail and the features forming the invention then specifically pointed out in the claims.

In the drawings,—

Fig. 1 is a vertical section showing an 35 exhaust check valve of the preferred form embodying the invention in its most complete form;

40 Fig. 2 is a similar view showing a modified construction with cushioning in only one direction.

Referring to the drawings, the valve casing 10 is provided with branches 11 and 12, the branch 11 being normally the inlet branch, and branch 12 the outlet branch to 45 the heater. The upper end of the casing 10 is closed by a suitable cap 13. The valve seat 14 is secured in any manner in valve deck 15 and carries through suitable webbing a central hub 16 having its center cored 50 out as shown. A suitable valve 17, preferably of the plate type, coacts with the valve seat 14, and is provided with a central opening through which passes a valve guide 18.

55 To cushion the opening movement of the valve 17 I provide a cushion chamber 19

above the valve and preferably cast integral- 20 ly with the cap 13 and an extension 60 thereon. An important feature of the invention comprises the provision of means for adjusting or regulating the effective size 65 of the cushion chamber 19 to control the cushioning of the valve 17. This regulating means may advantageously be of the form shown in which I provide a regulating disk or plate 21 within the cushion chamber 19. The disk 21 is secured between nut 22 and a shoulder, forming, as shown, the end of the valve guide 18, on a stud or bolt 23 screw-threaded in the extension 20 for 70 adjustment. A suitable lock nut 24 may be provided for locking the disk 21 in its adjusted position. The invention as thus far described embodies a flow from passage 11 to passage 12 as shown by the arrows in 75 Fig. 2.

A further feature comprises means where- 80 by the valve may be used with flow in the opposite direction or in normal use a por- 85 tion of any temporary back flow is directed against the lower side of the valve to aid 80 in holding the valve open and to cushion its closing movement. Referring particularly to Fig. 1, the valve seat 14 is formed with a portion projecting well above the valve deck 15 and provided with a suitable num- 85 ber of side ports 1 connecting passage 12 with passages 2 which open at the upper edge of the valve seat 14 and form ports closed by the valve 17. The through port 90 in the valve seat is preferably divided by one or more annular partitions 3 so that the steam passing through passage 2 against the valve flows inward toward the center of the valve for delivery through the seat to pas- 95 sage 11 which increases the lifting and cush- 100 ioning effect on the valve. By this means a portion of the back flow as shown by the arrows in Fig. 1 is directed upward against the valve in its seating movement, thus aiding in keeping it open and effectively cush- 105 ioning its seating. If the valve be used for a reverse flow, that is, from branch 12 to branch 11, the flow through ports 1 and pas- 110 sages 2 will open the valve, thus allowing flow to the through port connecting with branch 11.

By means of the regulating disk the effec- 110 tive cushioning of the valve may easily be regulated to meet the conditions of the serv- ice in which it is used. This device has the

further advantage that the regulating disk may be screwed down to force and hold the valve down against its seat so as to act as a shut off valve.

5. It will be understood that the invention is not limited to the construction shown and described as various modifications may be made therein within the invention as defined by the claims.

10. What is claimed is:

1. A check valve having a valve seat, a valve coacting with the seat, a cushion chamber for the valve, and a regulating plate movable to adjust the cushion chamber.

2. The combination with a valve seat and a valve, of passages for directing a portion of the back flow against the valve in a direction tending to open the valve whereby the 20 closing movement of the valve is cushioned.

3. The combination with a valve casing and valve seat, of a valve coacting with the valve seat, and ports and passages formed in the valve seat for directing a portion of 25 the back flow against the valve to cushion the closing movement of the valve.

4. The combination with a valve casing and valve seat, of a valve, a cushion for the opening movement of the valve, and pas-

sages for directing a portion of the back 30 flow against the valve to cushion the closing movement of the valve.

5. A check valve having a cushion chamber for cushioning the opening movement of the valve, and valve seat 14 having a 35 through port for flow in one direction, and ports 1 and passages 2 for directing flow in the opposite direction against the valve in a direction tending to open it.

6. A check valve comprising valve seat 40 14 having a through port for flow in one direction and ports 1 and passages 2 within the valve seat for directing flow in the opposite direction against the valve in a direction tending to open it. 45

7. A check valve comprising valve seat 14 having a through port for flow in one direction, annular partition 3 dividing said port, and ports 1 and passages 2 for directing flow in the opposite direction against 50 the valve in a direction tending to open it.

8. A check valve having valve disk 17, cushion chamber 19, disk 21 in said chamber, and adjusting bolt 23 carrying the disk and having a valve guide extension. 55

In testimony whereof, I have hereunto set my hand.

JOHN A. LE CAIN.
